UNITED STATES PATENT OFFICE.

FLETCHER B. GIBBS, OF CHICAGO, ILLINOIS.

COMBINED DESK BLOTTER-PAD AND CALENDAR.

SPECIFICATION forming part of Letters Patent No. 450,741, dated April 21, 1891.

Application filed November 28, 1890. Serial No. 372,833. (No model.)

To all whom it may concern:

Be it known that I, FLETCHER B. GIBBS, residing at Chicago, in the county of Cook and State of Illinois, and a citizen of the United States, have invented a new and useful Improvement in a Combined Desk Blotting-Pad and Calendar, of which the following is a specification, reference being had to the accompanying drawings, in which—

10 Figure 1 is a plan view, and Fig. 2 is a section on line 2 2 of Fig. 1.

The object of my present invention is to provide an improved desk blotting-pad adapted to receive a calendar and to provide an improved calendar adapted to be attached upon the blotting-pad, so that the calendar will at all times be in sight and be convenient for the purpose of making memoranda thereon.

I accomplish my object as illustrated in the drawings and as hereinafter described.

That which I claim as new will be pointed out in the claim.

In the drawings, the letter A indicates a base-board, having pockets a to receive the corners of one or more sheets a' of blotting-paper and provided above the same with supplemental pockets c for retaining a calendar-block B. The calendar-block B is made up in suitable form of a number of leaves or sheets 25 of paper, which are blocked together and mounted upon a flexible base A', having each end projecting as a flange b. The calendar-block B is adapted to be attached through the

medium of its projecting end flanges b entering the supplemental pockets c, formed on the 35 base-board. The flexibility of the base A' enables the calendar-block to be sprung into and out of the pockets c, as will be obvious.

By providing the base-board A with the supplemental pockets c it is readily and eco- 40 nomically adapted to receive the calendar-block B, and by the projecting end flanges b of the flexible base A' of the calendar-block the latter is readily and economically adapted to be secured in position on the base-board. 45

The improved construction provides a novel, desirable, and efficient blotting-pad and calendar, wherein the latter is at all times plainly in sight and convenient for the purpose of making memoranda thereon. 50

I do not broadly claim a combined blotting-pad and calendar; but,

Having thus described my invention, what I claim is—

A combined blotting-pad and calendar, consisting of a base-board A, having pockets a to receive the corners of blotting-sheets and supplemental pockets c in juxtaposition thereto, and a calendar-block having a base A', provided with opposite end flanges b, respectively engaging the supplemental pockets, substantially as and for the purpose described. 55 60

FLETCHER B. GIBBS.
